REFRIGERATING APPARATUS

Whitney Giffard, Detroit, Mich., assignor to
Nash-Kelvinator Corporation, Detroit, Mich., a
corporation of Maryland

Application August 15, 1947, Serial No. 768,917

4 Claims. (CL 62—116)

1

This invention relates generally to refrigerating apparatus and more particularly to refrigerators of the household type.

It is an object of the present invention to provide an improved arrangement of a refrigerator system and cabinet to increase the usable available storage space in the cabinet without affecting the efficiency of the system.

Another object of the invention is to provide a cabinet construction and arrangement for either a single, or two temperature system in which the usable, available storage space within the cabinet is increased.

Another object of the invention is to provide an improved arrangement for increasing storage capacity of removable receptacles located in the region of a cabinet machinery compartment.

Further objects and advantages of the present invention will be apparent from the following description, reference being had to the accompanying drawings, wherein a preferred form of the present invention is clearly shown.

In the drawings:

Fig. 1 is a front elevational view with door removed, of a refrigerator embodying features of the present invention;

Fig. 2 is a vertical, sectional view of the refrigerator taken along the line 2—2 of Fig. 1;

Fig. 3 is a horizontal, sectional view of the refrigerator taken along the line 3—3 of Fig. 1;

Fig. 4 is a diagrammatical view showing a two temperature type of refrigerating system for the refrigerator;

Fig. 5 is a vertical sectional view of modification of the invention, embodying features of my invention; and

Fig. 6 is a diagrammatical view of the refrigerating system of the refrigerator of Fig. 5.

Referring to the drawings and more particularly to Figs. 1 to 4 inclusive, the household refrigerator shown includes a cabinet, designated generally by the numeral 20. The cabinet 20 has a food storage compartment 22, a freezing compartment 24 and a cooled, high humidity compartment 26. In the present cabinet, the freezing compartment 24 is located above the food storage compartment 22, adjacent the top of the cabinet and the high humidity compartment 26 is located below the food storage compartment, adjacent the bottom of the cabinet. The cabinet 20 has a bottom wall 28, side walls 30, a rear wall 32, a top wall 34 and a door 36. As shown, the door 36 extends substantially the full height of the cabinet, closing the compartments 22, 24 and 26. An inner door 38 is preferably provided for

2

the freezing compartment 24 so that room air will not freely enter this compartment when the main or outer door 36 is opened.

The cabinet 20 comprises a metal casing 40 and upper metal liner 42 and a lower metal liner 44. Liner 42 forms the walls of the freezing compartment 24 and liner 52 forms the walls of the food storage compartment 22 and of the high humidity compartment 26. Interposed between the liners 42, 44 and the casing 40 is insulation 46 which may be of any suitable type. Insulation is also interposed between the adjacent top and bottom walls of the liners 42, 44 providing a horizontal insulation partition 48 between the freezing compartment 24 and the food storage compartment 22. Imbedded in this horizontal partition 48, a horizontally disposed baffle plate 50 is provided to prevent circulation of air, in the insulation, above and below the baffle or so that the liners will be sealed from each other to circulation of air therebetween. This baffle plate 50 extends to the side and rear wall inner surfaces of the cabinet casing 40 and to the front of the horizontal partition 48 between the liners.

The refrigerating system comprises, in general, a relatively high temperature refrigerant evaporator 52, a relatively low temperature refrigerant evaporator 54, a refrigerant condenser 56 and a refrigerant motor-compressor unit 58. As shown, the evaporators 52 and 54 are preferably sinuous conduits or coils, respectively secured to the outer surfaces of the liners 42 and 44. In the present arrangement, the evaporator coil 52 extends along the rear wall of the liner 42 and the evaporator coil 54 extends along the bottom, sides and top of the freezing compartment liner 44. Liquid refrigerant is supplied from the condenser 56 to the relatively high temperature evaporator 52 through a control or capillary tube 60, absorbing heat from the liner 42 to cool the food storage compartment 22. From the evaporator 52, the refrigerant flows into the relatively low temperature evaporator 54 through a flow restricting tube 62 which maintains a pressure differential between the evaporators. A vapor return line 64 connects the relatively low temperature evaporator 54 to the motor-compressor unit 58 where the refrigerant is compressed and delivered to the condenser 56.

The motor-compressor unit 58 is located in a machinery compartment 66, adjacent the bottom and rear walls of the cabinet. This unit 58 may be suitably mounted on the base frame of the cabinet. In order to increase the available, usable storage space of the cabinet, I form the

cabinet rear wall 32 with an inwardly extended portion 70, intermediate the cabinet side walls 30 to provide a recess for receiving the motor-compressor unit 58. This extended portion 70 is rounded or arcuate, as shown, to decrease cabinet storage space occupied thereby. A flue 72 and the rounded recessed wall portion 70 cooperate to form the machinery compartment 66 for the motor-compressor unit 58. To aid up draft of air through the machinery compartment so as to carry away the heat generated by the motor-compressor unit, the extended rear wall portion 70 may be inclined, extending downwardly and forwardly to join the cabinet bottom wall 28, intermediate the front and rear walls of the cabinet. To increase further the available, usable storage space in the cabinet, the rounded, extended portion 70 of the cabinet rear wall is made conical in shape; the cross sectional area of the recess formed thereby decreasing upwardly to the point where the extended portion 70 joins the vertical rear wall 32.

In the food storage compartment 22, a number of vertically spaced shelves 86 is provided and supported on rails secured to the liner 42. Preferably, the shelves 86 are made of glass or other suitable impervious material to baffle and decrease air circulation throughout the compartment 22. Some air circulation is permitted in the food storage compartment by spacing the shelves, as at 88, slightly from the liner rear wall. A horizontal partition and shelf 90 which may also be made of glass, completely closes off a lower region of the high humidity compartment 26 from the food storage compartment 22. Immediately above and beneath the partition 90 are storage drawers 92 for fresh vegetables. These drawers 92 each have inclined rear walls which are contoured having conically shaped recesses 93 to conform or to position substantially complementary with the extended portion 70 in the cabinet rear wall. These conical recesses 93 in the rear walls of the drawers 92 are disposed between the drawer sides and provide for increasing the usable, available drawer space. It will be seen, that since the extended portion 70 is conical in shape, the upper drawer near the apex of the cone requires less of a clearance offset in the rear wall thereof, thus increasing the capacity of this drawer.

In the freezing compartment 24, ice cube trays 94 are positioned beneath a shelf 96, seating on the bottom wall of the liner 44. The freezing compartment shelf 96 is provided to support foods to be frozen.

Referring now to the modification of Figs. 5 and 6, the refrigerator shown is similar to the previously described refrigerator and therefore like parts are designated by like numerals to avoid unnecessary repetitious description. The refrigerator of Figs. 5 and 6 differs from the refrigerator of Figs. 1 to 4 inclusive in that the former is a single temperature refrigerator having an evaporator 100 for cooling the food storage compartment 102. This evaporator 100 may be suspended by suitable brackets 104 from the top wall of the cabinet and cooperates with the cabinet liner to form an upper food storage compartment 106 and a lower, high humidity storage compartment 107. The compartment 107 is cooled by the evaporator 100 and high humidity is effected therein by maintaining the proper temperature and by restricting air flow between compartment 107 and the evaporator 100. In the food storage compartment 106 a

number of shelves 108 may be provided which are preferably wire shelves to allow free circulation of air throughout the food storage compartment. Limited circulation of air between compartment 106 and 107 is allowed by spacing the rear edge of the partition 105 slightly from the rear wall liner of the cabinet. A motor-compressor 109 is received in an inclined, conical portion of the cabinet rear walls, intermediate the side walls thereof so as to increase the available, usable storage space in the cabinet. A condenser 111 which is preferably attached to the inner side of the cabinet casing supplies refrigerant through a capillary tube 112 to the evaporator 100 whence the refrigerant returns through a conduit 114 to the motor-compressor unit 106.

From the foregoing description it will be noted that I have provided an improved arrangement of a cabinet and a refrigerant motor-compressor unit to increase the available, usable storage space in a cabinet. It will further be noted that by the provision of an arcuate recess in the cabinet rear wall for the motor-compressor unit that receptacles forwardly of this recess may have enlarged capacities. In addition, by using a conical-shaped recess, a saving in storage space is effected and air flow through the motor-compressor conical compartment is induced or enhanced by the inclination of the recessed wall.

Although only a preferred form of the invention has been illustrated, and that form described in detail, it will be apparent to those skilled in the art that various modifications may be made therein without departing from the spirit of the invention or from the scope of the appended claims.

I claim:

1. In refrigerating apparatus, a cabinet storage compartment having rear and bottom walls, a refrigerant evaporator arranged to cool said compartment, a refrigerant condenser operatively connected to said evaporator, a cabinet machinery compartment at the bottom and rearwardly of said storage compartment, a conical wall common to said compartments, said conical wall converging upwardly from said cabinet bottom wall to said cabinet rear wall, a refrigerant motor-compressor unit in said machinery compartment operatively connected to said evaporator and to said condenser, and a storage container in said storage compartment conforming at the rear substantially complementary to said conical wall.

2. In refrigerating apparatus, a cabinet storage compartment having rear and bottom walls, a refrigerant evaporator arranged to cool said compartment, a refrigerant condenser operatively connected to said evaporator, a cabinet machinery compartment in the bottom and rearwardly of said storage compartment, a conical wall common to said compartments, said conical wall converging upwardly from said bottom wall joining the cabinet rear wall intermediate the top and bottom thereof, a storage container in said storage compartment having a rear wall conforming substantially complementary to said conical wall, and a refrigerant motor-compressor unit operatively connected to said evaporator and to said condenser and being disposed in said machinery compartment entirely above the outer surface of said cabinet bottom wall.

3. In refrigerating apparatus, a cabinet storage compartment having rear and bottom walls, a refrigerant evaporator arranged to cool said compartment, a refrigerant condenser operatively

connected to said evaporator, a cabinet machinery compartment adjacent the bottom and at the rear of said storage compartment, a conical wall converging upwardly from the cabinet bottom wall intersecting the cabinet rear wall intermediate top and bottom walls of said storage compartment, said conical wall being common to said storage compartment and machinery compartment, an upper shelf substantially at the point of intersection of said conical wall and said cabinet rear wall, a lower shelf having a rear edge conforming in contour to said conical wall, containers between said shelves and between said lower shelf and said cabinet bottom wall conforming at the rear to the contour of said conical wall, a refrigerant motor-compressor unit disposed within said machinery compartment generally conforming in contour to said conical wall, said motor-compressor unit being operatively connected to said refrigerant evaporator and to said condenser, and a flue member overlying the conical recess cooperating therewith to induce up-draft through said machinery compartment.

4. In a refrigerating apparatus, a cabinet having storage space extending substantially from

5 top to bottom of said cabinet and having side and rear walls, a refrigerant evaporator arranged to absorb heat from at least a portion of said storage space, a conical rear wall portion intermediate said side walls forming a recess in the rear of said cabinet, said conical wall portion being inclined between the front and rear walls of the cabinet projecting into the storage space, a refrigerant motor-compressor unit disposed part way into said recess, a refrigerant condenser operatively connected to said evaporator and to said motor-compressor unit, and a storage receptacle in said storage space having a conical recess complementary to said conical rear wall portion.
